(57) **CLAIM**

The ornamental design for an LED work light assembly, as shown and described.

DESCRIPTION

FIG. 1 is a top, front, and right side perspective view of an LED work light assembly showing my new design;

FIG. 2 is a top, rear, and left side perspective view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken line disclosure of a power tool battery on the rear of the assembly forms no part of the claimed design.
